Eli Sawyer

UNITED STATES PATENT OFFICE.

ELI SAWYER, OF BARRE, VERMONT.

TRACE-PUNCH.

SPECIFICATION forming part of Letters Patent No. 549,216, dated November 5, 1895.

Application filed September 24, 1894. Serial No. 523,972. (No model.)

To all whom it may concern:

Be it known that I, ELI SAWYER, a citizen of the United States, residing at Barre, in the county of Washington and State of Vermont, have invented a new and useful Trace-Puncher, of which the following is a specification.

My invention relates to improvements in trace-punching machines in which an under and upper punch are brought into simultaneous action in punching a trace; and the objects of my invention are, first, to provide a trace-puncher conveniently operated by hand-levers; second, to punch the trace from both sides simultaneously; third, to provide facilities for clearing the knives of the core cut out when the trace is punched; fourth, to so punch the trace as to leave both sides of the edges of the hole made in the trace smooth and unfrayed. I attain these objects by the mechanism illustrated in the accompanying drawings.

Figure 1 is a perspective view of the entire structure of the trace-puncher in a position ready for operation. Fig. 2 is a vertical front view of the trace-puncher when not in use. Fig. 3 is a front view of the knives of puncher with trace inserted between them. Fig. 4 is a vertical side view of the trace-puncher with handles or levers up, as structure is when not in use. Fig. 5 is a side view of the trace-puncher with handles or levers down. Fig. 6 is a view of the knives of the trace-puncher inserted through the trace with the core-cleaner pressed down. Fig. 7 is a side view of the entire structure of the trace-puncher with lever down and core-cleaner in position after driving out the core.

Lever A, Fig. 1, is attached to frame R by bolt S. Lever B is attached to lever A by bolt U. Punch L is kept in place by cleats T T, and engages at its upper end lever A in the slot just in front of bolt S, and is constantly in contact with lever A by means of an upward pressure of spring J. Spring J is attached to punch L by a lug engaging the upper end of spring J. Spring J, acting upon punch L as above described, holds up lever A in position shown in Fig. 1. Spring J at its lower end rests upon framework R, where it projects forward at P and separates into two standards, between which spring J is placed. Trace-

receiver G consists of a plate with a flange at the front and back side, into which the trace is placed, and this plate is riveted to spring D. 55 Spring D is attached to frame R by a screw inserted through it on the right end that laps over the base of frame R. The other or left end of spring D is free and extends in a left-hand direction when flattened by downward pressure, which it receives when the punch is operated. Punch F projects upward through an aperture in trace-receiver G. Frame R is attached to table P P by bolts or otherwise. Punch F is attached by clip H to base of frame 60 Q by bolts. X shows the opening of punch F at the top of trace-receiver G. Y is the opening of punch F where core of trace drops through after trace is punched. Core-cleaner C is attached to lever B by bolt V and its 65 lower end is held in position by a slot in punch L, through which it passes when driving out the core, as shown in Fig. 7.

The punch is operated by inserting the trace M in receiver G, as shown in Fig. 3. The lever 75 A is operated with the hand by downward pressure, bringing it into position shown in Fig. 5. The downward movement of lever A forces punch L partially through the trace, and the receiver G, under the force of this 80 downward movement of lever A, recedes and allows the under punch F to cut upward into the trace as the trace is forced down upon punch F when the lever A is brought into the position shown in Fig. 5. Punch F is stationary. The two punches L and F are brought together midway between the upper and lower sides of the trace, and the core, when taken out, leaves the hole N in the trace as shown 85 Fig. 6. This core, if the lever A were returned 90 to position as shown in Fig. 1, would remain in the trace or in one of the punches L or F. To clean the punches, lever B, when lever A is in position as shown in Fig. 5, is pressed upward by the fingers against the lever A, as 95 shown in Fig. 7. This drives the punch-cleaner C downward into position as shown in Fig. 7 and the core is forced out of the opening Y in punch F. The result is a clean-cut 100 hole with unfrayed edges without a core being left either in the trace or in either of the punches, as shown by hole N, Fig. 6.

What I claim as my invention, and desire to secure by Letters Patent, is—

1. A trace punch comprising a suitable frame, a fixed punch F, a movable punch L, a bar to which the movable punch is attached, a lever A attached to the frame and engaging the bar, and lever B pivotally connected with the lever A, and a core cleaner C movable within the punch L and operated by the lever B, all substantially as set forth.
2. In combination, in a trace punch a suitable frame, two punches, one of which is movable toward the other, a trace receiver yieldingly supported above the fixed punch, a core cleaner within the movable punch, a lever A attached to the frame and operating the movable punch, and a lever B pivotally connected with the lever A and operating the core cleaner, all substantially as set forth.
3. The combination of a frame R, a fixed punch F attached thereto, a trace receiver yieldingly supported above the fixed punch, 20 a movable punch L, a bar to depress the punch, an elevating spring supporting the bar and withdrawing the movable punch L after depression, a lever A pivotally attached to the frame and engaging the bar, a lever B pivotally connected to the lever A and a core cleaner C connected with the lever B and movable within the punch L, all substantially as described.

ELI SAWYER.
